UNITED STATES PATENT OFFICE.

JOHN M. PHILLIPS, OF GILLSVILLE, GEORGIA.

SULKY-PLOW.

SPECIFICATION forming part of Letters Patent No. 257,063, dated April 25, 1882.

Application filed February 21, 1882. (Model.)

To all whom it may concern:

Be it known that I, JOHN M. PHILLIPS, of Gillsville, in the county of Banks, and in the State of Georgia, have invented certain new and useful Improvements in Sulky-Plows; and I do hereby declare that the following is a full, clear, and exact description thereof, reference being had to the accompanying drawings, and to the letters of reference marked thereon, making a part of this specification.

This invention has for its objects to provide a sulky-plow the parts of which will be adjustable with respect to each other, to adapt the plow to various descriptions of work, as more fully hereinafter specified. These objects I attain by the apparatus and mechanism illustrated in the accompanying drawings, in which—

Figure 1 represents a perspective view of my improved plow, and Fig. 2 a longitudinal vertical sectional view thereof; and Fig. 3, a perspective view of a modification of my plow.

The letter A indicates the frame of the apparatus, which is secured to the bent axle B, near the ends, by means of the clips C, plates D, and nuts E.

The letter F indicates the wheels of the plow, which are secured to the journals of the axle in any convenient manner. The elevated portion of the axle is on a level with the front and rear ends of the frame, and with such front and rear ends forms a support for the tongue G.

The letter H indicates two metallic segments, which are secured to the sliding boxes I on the front and rear parts of the frame, whereby they may be moved and adjusted laterally, as and for the purpose more fully hereinafter specified. The boxes are held in place when adjusted by means of the set-screws K. To said

boxes are secured the stirrups L, which are provided with guides M for the plow-beams N, which beams are pivoted to boxes P, adapted to slide vertically upon the forward portions of the stirrups.

The letter R indicates two standards, permanently secured to the segments and adjustably to the axles by means of the clips C. These have pivoted to them the levers S, which connect with the elbow-levers T, by means of which the plow-beams are elevated or depressed at the rear. The levers S are provided with thumb-latches U, which are adapted to engage re-

cesses V in the edges of the segments and hold the levers and plow-beams in any desired position. The stirrups are braced by means of straps W, adjustably secured to the axle by means of the clips C, before mentioned.

The letter A' indicates two segments, attached to the stirrups and provided with levers B', connecting by means of the compound levers C' with the boxes P, by means of which the said boxes and the forward ends of the plow-beams may be adjusted and held in place. The segments are perforated to receive a pin on the levers, in order to hold the same in any required position.

It will be perceived that the parts which support the plows and the mechanism for elevating and depressing the same are adjustable laterally, so as to carry plows of different sizes and permit them to be set at different distances apart.

In the modification shown in Fig. 3 the plow-standards are adjusted by means of the sliding clips D' and set-screws E', one of the clips being seated on the plow-beam and the other on a bracket, F', attached thereto, the clips being connected with the standards by means of links G', the lower edges of the beam and bracket being serrated, as shown, to give the clips a better hold.

Having thus described my invention, what I claim, and desire to secure by Letters Patent, is—

1. The combination, with the frame A and axle B, of the adjustable segments H and sliding boxes I, the stirrups P, L, the plow-beams N, pivoted thereto, and the compound elbow-levers T and operating-lever S, all constructed and arranged to operate in the manner specified: 85

2. In combination with the segments A', the levers B' and C', the sliding boxes P, mounted upon the stirrups L, and the plow-beams N, pivoted to said boxes, all constructed and adapted 90 to operate substantially in the manner specified. 95

In testimony whereof I affix my signature, in presence of two witnesses, this 16th day of January, 1882.

JOHN M. PHILLIPS.

Witnesses:

G. W. YORK,
S. P. BUFFINGTON.
